ALEXIS R. PRIBIL, OF DETROIT, MICHIGAN.

CARBURETER.

1,080,166.

Specification of Letters Patent.

Patented Dec. 2, 1913.

Application filed October 4, 1911. Serial No. 652,778.

To all whom it may concern:

Be it known that I, ALEXIS R. PRIBIL, a citizen of the United States of America, residing at Detroit, in the county of Wayne 5 and State of Michigan, have invented certain new and useful Improvements in Carbureters, of which the following is a specification, reference being had therein to the accompanying drawings.

- 10 This invention relates to improvements in carbureters and more particularly to means for automatically regulating the flow of air therethrough in accordance with the speed of the engine.
- 15 The object of the invention is to provide simple and efficient means for controlling the operation of the air inlet valve to prevent irregularity in its opening movement and to provide certain new and useful features in the construction and arrangement of parts; the invention consisting in the matters hereinafter set forth and more particularly pointed out in the claims, reference being had to the accompanying drawing in 25 which.

Figure 1 is a vertical section on the line $x-x$ of Fig. 2 through a carbureter embodying the invention; Fig. 2 is a horizontal section of the same on the line $y-y$ of Fig. 1; 30 and Fig. 3 is a sectional detail on the line $z-z$ of Fig. 1.

This invention is applicable to any form of carbureter having a chamber to which gasolene is supplied and taken up by air drawn through the chamber by the suction stroke of an engine, but for convenience of illustration, a construction is shown in which a cast metal casing is formed with a body portion 1 and a laterally extending portion 2 35 forming a float chamber of any desired construction to which gasolene is supplied through a pipe 3 and from which it is conducted into the lower end of the body 1 by a pipe 4.

40 The body of the carbureter forms an enlarged air chamber 5 and a reduced tubular extension 6 on the body, forms a mixing chamber 7 above the air chamber. The upper end of the extension 6 is formed with a laterally extending flange 8 by means of which the carbureter may be attached to an engine manifold or other part to deliver explosive charges to an engine cylinder upon the suction stroke of its piston. Within the 45 extension 6 at the upper end of the mixing chamber is the usual throttle or butterfly

valve 9 for controlling the flow of the explosive charges to the engine.

The body 1 is provided with a screw-threaded opening in its lower end into which is screwed a hollow cap 10 formed with a peripheral opening covered by a wire gauze or screen 11 through which air is drawn into the carbureter. The lower disk or end 12 of the cap is formed with an inwardly extending hub portion 13 through which the gasolene supply pipe 4 extends vertically upward into the air chamber 5 with a spray nozzle 14 on its upper end adjacent the lower end of the mixing chamber 7. The inner or upper end of the cap 10 is formed with an axial air inlet opening 15, and fitting within this opening is a vacuum valve 16 having a lower head or disk 17 forming a closure for the opening 15 and provided with an axial opening through which the pipe 4 extends, the valve being adapted to slide freely upon the pipe. The valve head is also formed with an upwardly extending peripheral guide wall 18 upon which is a tubular sleeve 19 having an inwardly extending flange 20 at its upper end to engage the upper end of the wall 18 of the valve when the same is raised. A similar sleeve 21 is provided upon the sleeve 19 and a like sleeve 22 upon the sleeve 21, each of the latter sleeves being also provided with an inwardly extending flange 20 at its upper end to engage the upper end of the adjacent inner sleeve. These concentric sleeves are guided in their vertical movement by ribs 23 which extend radially inward from the wall of the air chamber, and each rib is formed with a shoulder 24 to engage the upper end of the outer sleeve 22 and limit the sleeves and valve in their upward movement. Lugs 25 are provided on the upper end of the cap 10 to extend upward into the chamber 5 at each side of the valve 16, and each of these lugs is formed with a notched inner edge forming stepped seats 26 for the lower ends of the sleeves to support said sleeves at different heights.

When inoperative position, as shown in Fig. 1, the valve 16 rests upon the upper end of the hub 13 of the cap with its lower end within the air inlet opening 15 which is closed thereby, and the several sleeves are supported at graduated heights by the stepped lugs 25. The air inlet is thus closed by the valve, but upon the suction stroke of the engine piston, said valve will

be lifted by the partial vacuum formed in the air chamber and air will be drawn in through the screen of the cap, upward through the opening 15 beneath the valve 5 and lower edges of the sleeves into the air chamber. When thus lifted, the upper end of the wall 18 of said valve comes into contact with the flange 20 on the sleeve 19 which sleeve forms a movable weighted stop 10 for the valve to prevent its being carried by its inertia beyond the point to which the suction alone would lift it. When given free unlimited movement, the operation of the valve is therefore irregular, but by placing 15 the weighted stop in its path, the valve will always be stopped at a certain height when actuated by a given vacuum and will not rise higher until the suction increases sufficiently to overcome the added weight of 20 the sleeve 19 when said sleeve will be lifted by the valve. Further increase in the speed of the engine and consequent increased vacuum will lift the valve and sleeve 19 until the upper end of said sleeve comes into 25 contact with the flange on the sleeve 21. This sleeve 21 thus becomes a weighted movable stop to arrest the upward movement of the valve until the vacuum increases sufficiently to lift the valve and both of the 30 sleeves, and the sleeve 22 serves in a like manner, as a third movable stop. The valve is thus arrested in its upward movement at three different points, preventing any perceptible variation in its operation due to 35 inertia or inability to respond quickly to the rapid variations in the vacuum. If a very light valve is used in order to obviate the difficulty arising from inertia, it will open too freely and will not have sufficient weight 40 to cause it to fall quickly with the variations in the vacuum, but by providing the stop members which are picked up by the valve at different points in its upward movement, the valve is weighted in proportion to the 45 vacuum and caused to act quickly in its closing movement, at the same time permitting the use of a comparatively light valve which will open quickly in starting.

Obviously, changes in the details of construction may be made without departing from the spirit of my invention and I do not wish to limit myself to the particular construction and arrangements of the parts shown.

Having thus fully described my invention what I claim is:—

1. In a carbureter comprising a casing having an air chamber provided with an air inlet and an outlet, the combination of a 50 valve member for controlling the air inlet adapted to be automatically operated by suction, movable stops in the path of the opening movement of said valve, and a fuel supply member opening into said chamber 55 above said valve.

2. In a carbureter comprising a casing having an air chamber provided with an air inlet and an outlet, the combination of a valve member controlling the air inlet adapted to be automatically operated by 70 suction, a movable gravity stop in the path of the opening movement of said valve, and a fuel supply member extending through said valve member and opening into said chamber.

3. In a carbureter comprising a casing having an air chamber provided with an air inlet and an outlet, the combination of a fuel supply member extending into said chamber through the inlet, a valve surrounding said supply member and controlling the inlet adapted to be automatically operated by suction, and a plurality of movable members positioned at intervals along the path of travel of the valve to form an increasing 85 resistance to the opening of said valve.

4. In a carbureter comprising a casing having an air chamber provided with an air inlet and an outlet, the combination of a fuel supply member extending vertically 90 through said inlet into said chamber, a valve surrounding the member to control the inlet and adapted to be automatically operated by suction, a series of concentric gravity members in the path of the opening movement of 95 the valve, and means for supporting said gravity members at different heights to be successively lifted by the valve.

5. In a carbureter comprising a casing having an air chamber provided with an air 100 inlet and an outlet, the combination of a fuel supply member extending vertically through the inlet into said chamber, a valve slideable upon said member for controlling the inlet and adapted to be lifted by suction, 105 and a gravity member supported above said valve concentrically therewith to be engaged and lifted thereby.

6. In a carbureter comprising a casing having an air chamber provided with an air 110 inlet and an outlet, the combination of a valve controlling the inlet adapted to be automatically operated by suction, a plurality of concentric gravity members adapted to be successively engaged and lifted by the 115 valve, and means having seats at different heights for supporting said members concentrically with the valve.

7. In a carbureter comprising a casing having an air chamber provided with an air 120 inlet and an outlet, the combination of a valve member controlling the inlet and adapted to be automatically operated by suction, a gravity member surrounding the valve member to be lifted by the upward 125 movement of said valve, and means in the chamber for guiding the gravity member and forming a seat to support said member above the valve member when the same is in lowered position.

8. In a carbureter comprising a casing having an air chamber provided with an air inlet and an outlet, the combination of a cylindrical valve adapted to be operated by suction, a plurality of concentric sleeves on said valve adapted to be successively raised by the upward movement of the valve, means for supporting said sleeves at different heights, and guides for said sleeves in said chamber.
9. In a carbureter comprising a casing having an air chamber provided with an air inlet and an outlet, the combination of a fuel supply member extending upward in the axis of said inlet into said chamber, a valve slidable upon said supply member to control the air inlet, a plurality of concentric tubular gravity members surrounding the supply member and valve, and means within the chamber for guiding said tubular members and stepped ribs for independently supporting said members at different heights.
10. In a carbureter comprising a casing having an air chamber provided with an air inlet and an outlet, the combination of a valve controlling the inlet adapted to be operated by suction and formed with a peripheral wall, a plurality of sleeves sleeved upon said wall and upon one another, means upon the upper end of each sleeve adapted to be engaged by an adjacent sleeve when the same is raised, a plurality of ribs in the air chamber forming guides for the outer sleeve, and members having stepped inner sides forming seats to be engaged by the lower ends of the sleeves and support the same at different heights.
11. In a carbureter comprising a casing having an air chamber provided with an air inlet and an outlet, the combination of a valve for controlling the inlet adapted to be operated by suction and formed with a vertical peripheral wall, a plurality of gravity members sleeved upon said wall and upon each other, each member being formed with an inwardly projecting flange at its upper end, a plurality of ribs in the air chamber forming guides for the outer sleeve member, members having stepped inner sides forming seats to support the sleeves at different heights, and a fuel supply pipe extending upward through the valve at its axis and opening into the air chamber.

In testimony whereof I affix my signature in presence of two witnesses.
